United States Patent Office

Des. 194,524
Patented Feb. 5, 1963

194,524

PLASTIC SHEET MATERIAL OR SIMILAR ARTICLE

Wallis E. Stuart, Hingham, Mass., assignor to Air Reduction Company, Incorporated, New York, N.Y., a corporation of New York

Filed July 25, 1962, Ser. No. 71,054

Term of patent 7 years

(Cl. D87—3)

Fig. 1

Fig. 2

FIGURE 1 is a plan view of a plastic sheet material or similar article showing my new design; and

FIGURE 2 is a plan view of a portion of the sheet material shown in FIGURE 1 on an enlarged scale.

I claim:

The ornamental design for a plastic sheet material or similar article, as shown.
